UNITED STATES PATENT OFFICE.

JOSEPH A. MANAHAN, OF NEW YORK, N. Y.

FLAG-ILLUMINATING DEVICE.

Specification of Letters Patent. Patented Apr. 16, 1918.

1,263,090.

Application filed April 24, 1917. Serial No. 164,150.

To all whom it may concern:

Be it known that I, JOSEPH A. MANAHAN, a citizen of the United States, residing at New York, county of New York and State of New York, have invented new and useful Improvements in Flag-Illuminating Devices, of which the following is a specification.

This invention relates to a device for illuminating a flag or pennant and it is essentially adapted for attachment to a motor vehicle.

The invention is designed to provide a lamp with means for mounting a flag, and a device for projecting the light from the lamp onto a waving flag while the vehicle is in motion.

The object of the invention is to provide a simple and efficient device combining a lamp with a holder which can be readily mounted on the radiator or wind shield of an automobile.

The novel features of the invention are more fully described in the following specification and claims and illustrated in the accompanying drawing in which:

Figure 1 represents a front elevation showing the device attached to the front portion of a radiator.

Fig. 2 is a side elevation of the same.

Fig. 3 is a front view showing the device on a larger scale.

Fig. 4 is a plan view of the same.

In this drawing, the letter *a* designates a lamp casing which is provided with a small incandescent electric light *c* mounted in the casing. The casing has lateral openings respectively covered by ornamental colored glass or mica *b* and *d*. The casing also carries a lens *e* extending about the top of the casing and made to throw the light upward. A flag holder *f* is preferably located at the forward portion of the casing, and a screw *g* prevents withdrawal of a flag pole *h* when inserted in the holder or socket thereof.

The devices for securing the lamp to an object include a swinging member *i* which serves as a support for mounting the lamp casing as shown. The member *i* is swingingly pivoted at *j* to a pair of springy clamping members *k* made to encircle a mouth or neck at the forward top portion of a radiator as indicated in Figs. 1 and 2. To one end of the clamping members is secured a latch bar *m* for engagement with recesses *n*

formed in the lower bifurcated part of the 55 swinging support.

It will be seen, that when the swinging support is in engagement with the latch bar, the lamp casing will be firmly fixed to the radiator mouth. But when it is desired to 60 fill the radiator, the swinging support can be snapped out of engagement with the latch bar and operated to swing out of the way, as indicated by the dotted lines in Fig. 3, so that the cap can be removed from the mouth 65 for filling the radiator. When the flag is in position with the vehicle in motion, the light from the top lens will strike the flag on both of its sides giving it a radiant, luminous appearance.

I claim:

1. In a flag illuminating device, the combination with a pair of clamping members to engage an object, of a lamp casing extending over the object pivotally connected 75 to the members, made to swing out of the way of the object, the casing having means for projecting a light upwardly, and a holder carried by the casing.

2. In a flag illuminating device, the combination with a pair of springy clamping members to engage an object, of a lamp casing pivotally connected to the clamps, the casing having means for projecting a light 80 upwardly, and a holder located at the front 85 of the casing.

3. In a flag illuminating device, the combination with a pair of springy clamping members made to embrace an object, of a lamp casing pivotally connected between the 90 members, the casing having a lens for projecting a light upwardly, and a holder located at the front of the casing for receiving a pole.

4. In a flag illuminating device, the combination with a lamp casing, of a holder carried by the casing for mounting a flag, means for clamping the casing to an object, a support for the casing swingingly connected to the clamping means, and a latch for locking 100 the support to the clamping means.

In testimony whereof I have hereunto set my hand in the presence of two subscribing witnesses.

JOSEPH A. MANAHAN.

Witnesses:

W. M. E. WARLAND,
WILLIAM MILLER.
